CLAIM

The ornamental design for a scoop tub toy holder, as shown and described.

DESCRIPTION

FIG. 1 is a perspective view of one embodiment of a scoop tub toy holder.

FIG. 2 is a right side view of the scoop tub toy holder illustrated in FIG. 1.

FIG. 3 is a left side view of the scoop tub toy holder illustrated in FIG. 1.

FIG. 4 is a front view of the scoop tub toy holder illustrated in FIG. 1.

FIG. 5 is a back view of the scoop tub toy holder illustrated in FIG. 1.

FIG. 6 is a top view of the scoop tub toy holder illustrated in FIG. 1; and,

FIG. 7 is a bottom view of the scoop tub toy holder illustrated in FIG. 1.

The broken-line disclosure is understood to represent portions of the article in which the claimed design is embodied, but which form no part of the claimed design.
